UNITED STATES PATENT OFFICE.

CHARLES H. FOSTER, OF WASHINGTON, DISTRICT OF COLUMBIA.

OILING AND CLEANING DEVICE FOR GUNS.

1,154,390.

Specification of Letters Patent.

Patented Sept. 21, 1915.

Application filed September 17, 1914. Serial No. 862,130.

To all whom it may concern:

Be it known that I, CHARLES H. FOSTER, a citizen of the United States, residing in the city of Washington, District of Columbia, have invented a new and useful Oiling and Cleaning Device for Guns, of which the following is a specification.

My invention consists of a device for oiling and cleaning guns, in which the oil or 10 similar lubricant or cleaning liquid is introduced in the form of a spray acting against the walls of the bore.

It further consists of such a device which may be introduced into the bore of the gun 15 at the breech of the same and be moved through the entire length of such bore.

It further consists of such a device having a brush or swab for removing solid impurities from the bore.

20 It further consists of improved means for moving the spraying and cleaning device through the bore.

It further consists of other novel features 25 of construction, all as will be hereinafter fully set forth.

The annexed drawings and the following description set forth in detail one mechanical form embodying the invention, such detail construction being but one of various 30 mechanical forms in which the principle of the invention may be used.

In said annexed drawings, Figure 1 represents a side elevation of the entire oiling and cleaning device, illustrating the same in 35 position to be applied. Fig. 2 represents an axial section of a portion of a gun with the device in operative position. Fig. 3 represents an elevation, partly in section, of a reel for the air hose. Fig. 4 represents an 40 elevation of a disk or gate for closing the bore at the breech. Fig. 5 represents an elevation of the brush or swab.

Similar numerals of reference indicate 45 corresponding parts in the figures.

45 Referring to the drawings, the reference numeral 1 indicates the barrel of a gun, having a bore 2, and a threaded breech, 3, for the reception of the breech-block.

The oiling device comprises an oblong oil- 50 container, 4, preferably of substantially egg-shape, and having one or more filling necks, 5, closed by caps, 6. The outer end of the container has a spraying head or rose, 7, having perforations in its periphery to di-

rect its spray radially. A pipe, 8, is secured 55 in the inner end of the container and has a curved and foraminated portion, 9, within the container. Said pipe is secured by a coupling, 10, to a pipe-section, 11, which is connected to one branch of the casing of a 60 valve, 12, having its opposite branch connected to a pipe-section, 13, to which is secured a cylindrical brush or swab, 14, the body of which consists of two semi-cylindrical sections, 15, the joined centers of which 65 form a central opening, 16, which fits and is clamped upon the pipe-section 13, by means of spring-tongues, 17, upon one section engaging buttons or studs, 18, upon the other section. Collars, 19, upon the pipe-section 70 13 bear against the faces of the joined brush-body, confining the latter against movement upon the pipe-section. The pipe-section is secured in a coupling, 20, having an inclined outlet nozzle, 21, pointing toward the brush. 75 A flexible hose or pipe, 22, is secured to said coupling. A circular gate or disk, 23, is adapted to fit in the breech of the gun and to be secured by cams, 24, or other means to close the breech-end of the bore of the gun, 80 and said gate has a central opening, 25, in which the hose has a sliding fit.

For convenient stowage and moving of the hose, I provide a reel having a frame comprising an arched bail, 29, having a 85 handle, and two legs, 30, having feet, 31, and oblique braces, 32, having rollers, 33, journaled in their ends. The reel, proper, has a tubular axial hub, 34, and heads, 35, having radially projecting spokes, 36, and connected by rungs, 37, which form the drum of the reel upon which the hose is wound. One head of the reel has an axially projecting trunnion, 38, journaled in a bearing, 39, in one leg of the frame and having a detachable crank, 40, revolving the drum. A nipple, 41, extends from the tubular hub and has the end of the hose attached to it. The other head of the reel has a trunnion, 42, journaled in a bearing, 43, in the other leg 100 of the frame, and said trunnion has a large diameter axial bore, 44, the inner end of which communicates with the interior of the hub through a smaller bore, 45. An air-pipe, 46, has an enlarged head, 47, at its end, 105 formed with a port, 48, registering with the bore leading into the interior of the hub, and said enlargement is located within the

large bore and has a packing, 49, surrounding its inner portion. A tubular follower, 50, has its inner end bearing against said packing and has a shoulder, 51, bearing 5 against the outer end of the head and a ball-race in its outer end having anti-friction balls, 52. A cap, 53, is screwed upon the outer end of the trunnion and bears against said balls and through them against the follower. The air-pipe is coupled to a hose, 26, having its other end coupled to one of two branches, 27, having valves, 28, of an air conduit, 54.

In practice, the apparatus and reel are 15 placed near the breech-end of the gun, and the air-hose of the reel is coupled to the supply. The container is filled with oil or whatever lubricating or cleaning liquid is to be used, whereupon the container is inserted 20 through the breech into the bore of the gun. The brush or swab is inserted and the gate is secured in the breech. When air under pressure is admitted through the hose and pipe-connections, controlled by the valve 25 upon the same, it passes through the curved and foraminated pipe into the container, forcing liquid and air through the rose in a radial spray against the walls of the bore. The air passing through the inclined nozzle 30 fills the space between the brush and the gate in the breech and forces the brush and container toward the nozzle of the gun, lubricating the bore and softening the sediment, such as residue of powder or other 35 matter adhering to the bore, which will be removed and carried out by the brush or swab, the periphery of which may be covered with bristles, felt or similar covering.

When it is desired to positively move the 40 container and spray and the brush, the gate may be omitted and the brush and container pushed through the bore by means of rods or bars or any other suitable means. In either case whether the device is moved by 45 air or otherwise, the brush acts as a support and guide for the spraying device.

The hose has preferably numerals marked 50 upon it to indicate predetermined units of measure, so that the position of the container and spray and of the brush or swab within the bore of the gun can be ascertained at the breech-opening of the latter.

The apparatus can be easily moved from 55 one gun to another, and as the air-hose is coupled to one branch of the air-supply, the other branch will be accessible to attach other apparatus using compressed air from taps in an air-supply system now in general use in modern vessels and, particularly, in 60 war-vessels.

Other modes of applying the principle of 65 my invention may be employed for the mode herein explained. Change may therefore be made as regards the mechanism thus disclosed, provided the principles of construc-

tion set forth, respectively, in the following claims are employed.

Having thus described my invention, what I claim as new and desire to secure by Letters Patent is:—

1. In a device of the character stated, a liquid-container having a spraying head at one end, a conduit for air under pressure entering the opposite end of such container, and means for supporting and longitudinally moving and guiding such container within the bore of a gun.

2. In a device of the character stated, a liquid-container having a spraying nozzle at one end formed with apertures in its periphery, a conduit for air and having a curved and perforated portion within said container, and means for supporting and guiding such container within the bore of a gun.

3. In a device of the character stated, a liquid-container having a spraying nozzle at one end, an air-pipe connected to the other end of said container, a cylindrical brush upon said pipe to the rear of said container and adapted to slidably fit in the bore of a gun, and an air-conduit connected to said air-pipe.

4. In a device of the character stated, a liquid container having a spraying nozzle, an air-pipe connected to said container, a brush having a slidable fit in the bore of the gun and secured upon said air pipe to the rear of said container, an air-conduit connected to the air-pipe and provided with an outlet to the rear of said brush, and a gate adapted to be secured in the breech of the gun to close the same and having the air-conduit passing through it.

5. In a device of the character stated, a liquid container having at one end a spraying head formed with peripheral perforations adapted to throw radial jets, and an air-pipe entering the other end of the container and having the portion within the latter curved and foraminated.

6. In a device of the character stated, a liquid container having a spraying nozzle, an air pipe having its end perforated and terminating within said container, a brush having a slidable fit in the bore of the gun and secured upon said air pipe, an air conduit connected to the air pipe, a gate adapted to be located in the breech of the gun to close the same, and having said air conduit passing through it, and means for locking said gate within said breech.

7. In a device of the character stated, a liquid container having a spraying head at one end and adapted to introduce lubrication in the form of a spray against the walls of the bore, a conduit for air entering the opposite end of said container, and a brush having a sliding fit in the bore of the gun through which said air conduit passes, said

air conduit passing through said brush and having its free end perforated and terminating within said container.

8. In a device of the character stated, a liquid container having a spraying nozzle at one end, an air-pipe opening into the other end of said container, a brush upon such pipe and slideable in the bore of the gun, a gate adapted to close the breech of the gun,

and an air-conduit slideable in said gate and connected to said air-pipe and provided with an outlet-nozzle to the rear of the brush to admit air between the latter and the gate.
